C. W. KECKLER,
TELEPHONE EXCHANGE SYSTEM.
APPLICATION FILED OCT. 4, 1918.

1,352,970.

Patented Sept. 14, 1920.

Inventor:
Charles W. Keckler
by *J. E. Roberts* Atty.

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,352,970.

Specification of Letters Patent. Patented Sept. 14, 1920.

Application filed October 4, 1918. Serial No. 256,834.

To all whom it may concern:

Be it known that I, CHARLES W. KECKLER, a citizen of the United States, residing at Newark, in the county of Essex, State of 5 New Jersey, have invented certain new and useful Improvements in Telephone-Exchange Systems, of which the following is a full, clear, concise, and exact description.

This invention relates to telephone 10 exchange systems and more particularly to such systems in which link circuits are employed for interconnecting telephone lines.

In such systems it is desirable to provide means whereby the duration of telephone 15 conversations between subscribers' stations on interconnected lines may be restricted to a definite elapsed time.

It is the object of this invention to provide a system whereby a distinctive signal 20 is given upon the expiration of a predetermined time after the response of a called station.

To attain this object in accordance with one feature of the invention, an operator 25 and subscriber-controlled timing mechanism associated with an operator's link circuit and adapted for continuous operation for a predetermined period of time, is provided with operator-controlled means for maintaining its status at any time prior to the 30 expiration of the predetermined period.

It is thought that the nature of the invention will clearly appear from the following specification and the annexed drawing 35 in which the figure shows one embodiment of the invention.

In the accompanying drawing, line circuits leading from subscribers' stations A and B, which may be of any usual type, terminate 40 in jacks 1 and 3, respectively, at a central office, at which there is provided a plurality of link circuits C, which also may be of any suitable type, only sufficient portions thereof being shown to properly illustrate 45 the invention. An answering sleeve relay 5 and an answering supervisory relay 6 control an answering supervisory lamp 7. Similarly, a calling sleeve relay 8 and a calling supervisory relay 9 control a calling supervisory lamp 10. Relay 9 also controls the 50 operation of the timing mechanism which, although it may be of any suitable type, is shown as comprising a shaft 11 which is continuously rotated at a constant speed by a suitable driving means, not shown. An

electromagnet 12, associated with the shaft 11, is adapted to cause the engagement of a magnetic disk 37, carried by shaft 11, and a coöperating disk 13 mounted on a shaft 14, thereby causing the rotation of the latter 60 mentioned shaft. The member 13 is maintained free of the member 37 (as shown) by the spring-spider 22. Shaft 14 is also provided with a spring 15 adapted to normally maintain the arm 16, also secured to the 65 shaft, in its normal position against a stop pin 17 removably located in a fixed plate member 18. Additional apertures 19, 20 and 21 are provided in the member 18 for the reception of the stop pin 17 for selectively varying the normal position of the arm 16. A holding pawl 23, controlled by electromagnet 24, coöperates with a ratchet wheel 25, secured to the shaft 14, for maintaining such shaft and its associated arm 70 16 step by step in its advancement when rotated by disks 37 and 13. A contact 26 is adapted to be closed by the arm 16 when the shaft 14 has been rotated for the predetermined time. A relay 27, controlled by 75 the contact 26 connects an interrupter 28 in circuit with the lamp 10 to cause the intermittent lighting of such lamp, and a key 29 which although shown as a separate key, may conveniently be combined with the 80 usual operator's listening key 35, is provided for releasing relay 27. A holding key 30 removes the magnet 12 from the control of relay 9 so that the timing mechanism may be held in its advanced position by means 85 of holding pawl 23 at any step in its progression. The timing mechanism is further controlled by a resetting key 31, which not only removes magnet 12 from the control of relay 9, but also controls magnet 24 90 so that pawl 23 may be removed from engagement with ratchet wheel 25 and thereby permit spring 15 to restore the arm 16 to its normal position against the stop pin 17 located in the selected aperture of plate 18. 100

It is thought that the invention may be more fully comprehended from the following description of the operation of the system shown on the drawing.

Assuming that station A originates a call. 105 lighting the line lamp 33 in the usual manner in response to the operation of line relay 32, the operator in answering the call inserts plug 34 of link circuit C into jack 1, thereby operating the cut-off relay 2 and 110

the answering sleeve relay 5 over a circuit extending from battery, through the winding of relay 5, the sleeve contacts of plug 34 and jack 1 and the winding of relay 2 to ground. Relay 32 releases, due to the opening of the contacts of relay 2, and extinguishes lamp 33. Relay 6 also operates over a circuit extending from battery, through the winding of relay 6, the ring 5 contacts of plug 34 and jack 1, the ring conductor of the line circuit, the substation apparatus at station A, the tip conductor of the line circuit, the tip contacts of jack 1 and plug 34 to ground. The lighting of the 10 lamp 7 is thereby prevented. The actuation of listening key 35 connects the operator's telephone set (not shown) with the link circuit in the usual manner. Upon ascertaining that a connection is desired with station 15 B, the operator inserts plug 36 into jack 3. Relays 4 and 8 operate over a circuit extending from battery, through the winding of relay 8, the sleeve contacts of plug 36 and jack 3, and the winding of relay 4 to ground. 20 The closure of the contact of relay 8 lights lamp 10 over a circuit extending from battery, through the contact of relay 8, the lamp 10, the right-hand normal contact of relay 27, and the normal contact of relay 9 25 to ground. The station B is then signaled in any suitable manner and the response of such station thereto causes the operation of supervisory relay 9 over a circuit established from battery, through the winding of 30 relay 9, the ring contacts of plug 36 and jack 3, the ring conductor of the line circuit, the substation apparatus at station B, the tip conductor of the line circuit, the tip contacts of jack 3 and plug 36 to ground. The 35 opening of the normal contact of relay 9 extinguishes lamp 10 and the closure of the alternate contact thereof energizes magnet 12 over a circuit established from battery, through the left-hand normal contact of relay 27, the winding of magnet 12, the normal contact of key 31, the contact of key 30, and the alternate contact of relay 9 to ground. The member 13 is attracted by, and engaged with the magnetic disk 37, 40 whereupon shaft 14 is rotated in a clockwise direction against the effect of spring 15 and is held step by step in its rotation by the constant engagement of pawl 23 with the ratchet wheel 25. The arm 16 carried by the 45 shaft 14 leaves its position against the pin 17 and revolves with shaft 14 until it engages contact 26, whereupon relay 27 is operated over a circuit established from battery, through contact 26, and the winding of 50 relay 27 to ground. Relay 27 is locked over a circuit established from battery, through the contact of relay 8, the contact of key 29, and the middle alternate contact and winding of relay 27 to ground. Lamp 10 is re- 55 moved from the control of supervisory re- 60 lay 9 by the opening of the right-hand normal contact of relay 27 and is connected in circuit with the interrupter 28 by the closure of the right-hand alternate contact of relay 27 so that it is intermittently lighted over a circuit established from battery, through the contact of relay 8, the lamp 10, the right-hand alternate contact of relay 27 and the interrupter 28 to ground. The operator is 65 thus notified that the conversation has continued for the predetermined period and may then actuate listening key 35 to advise station A that the allotted time has expired. Relay 27 by opening its left-hand normal contact deenergizes magnet 12, and the 70 spring member 22 thereupon removes the member 13 from engagement with the magnetic disk 37. The closure of the left-hand alternate contact of relay 27 causes the energization of magnet 24 over a circuit extending from battery, through the left-hand alternate contact of relay 27, and the winding of magnet 24 to ground. Pawl 23 is 75 thereby removed from its engagement with the ratchet wheel 25 permitting spring 15 to 80 rotate shaft 14 in a counter-clockwise direction until arm 16 returns to its normal position against stop pin 17. The operator in response to the intermittent lighting of lamp 10 actuates key 29 which, as before 85 mentioned, may be associated with the listening key 35, thereby releasing relay 27 and extinguishing lamp 10. 90

When the station A discontinues the conversation and replaces the receiver on the switchhook, relay 6 is released to cause the lighting of lamp 7 over a circuit extending from battery, through the contact of relay 5, the lamp 7, and the contact of relay 6 to ground. If station B discontinues the 95 conversation prior to the engagement of arm 16 with contact 26, the relay 9 releases, causing the lighting of lamp 10 over a circuit established from battery, through the contact of relay 8, the lamp 10, and the normal contact 100 of relay 9 to ground. 105

In case the operator desires to hold the timing mechanism, key 30 is actuated, thereby opening the energizing circuit for magnet 12 and permitting the shaft 14 and the 110 associated arm 16 to be held in their advanced position by the pawl 23 engaging the ratchet wheel 25. Upon the release of key 30, the energization of magnet 12 causes the reengagement of members 37 and 115 120 13 and the further rotation of shaft 14 and arm 16 from the position occupied thereby, upon the actuation of key 30. In this manner the operator may converse with either 125 station without encroaching upon the period regularly allotted for a conversation between two connected stations. 130

It may be advisable in some instances to reset the timing mechanism prior to the expiration of the predetermined period and

the actuation of key 31 for this purpose not only causes the deenergization of magnet 12 as in the case of key 30, but also energizes magnet 24 over a circuit extending from 5 battery, through the alternate contact of key 31 and the winding of magnet 24 to ground. Pawl 23 thereupon being disengaged from ratchet wheel 25, the member 13 is removed from engagement with the 10 magnetic disk 37 and the spring 15 restores the timing mechanism to its normal position as previously described.

By placing the removable stop pin 17 in aperture 19, 20 or 21, which are spaced 15 upon the plate member 18 to give proper increments, the time occupied in the rotation of arm 16 before it closes contact 26 may be varied to meet the requirements of a 20 particular instance so that the flashing of lamp 10 will begin upon the expiration of any desired time after the response of the called station.

It will be evident from the foregoing description that this invention affords a simple 25 and convenient means, jointly controlled by the operator and the called station, for automatically notifying the operator upon the expiration of the time to be allotted for telephonic conversations, as well as permitting the operator to assume control of the timing mechanism when desired.

What is claimed is:

1. In a telephone exchange system, a plurality of lines terminating at a central office, a plurality of link circuits thereat for interconnecting the lines, a timing means for association therewith and adapted for continuous operation for a predetermined period, means controlled jointly by the operator and the subscriber on a connected line for starting the timing means, and operator-controlled means for holding the timing means at any time prior to the expiration of such period.
2. In a telephone exchange system, a plurality of line circuits terminating at a central office, a plurality of link circuits thereat for interconnecting the lines, a signaling device for each link circuit controlled over a connected line to produce signals, operator and subscriber-controlled step-by-step means for causing the signaling device to produce a different indication upon the expiration of a predetermined time after the response of 55 a called station, and operator-controlled means for holding the step-by-step means in its advanced position at any time prior to the expiration of the predetermined time.

3. In a telephone exchange system, a plurality of lines having subscribers' stations thereon and terminating at a central office, a plurality of link circuits thereat for connecting calling and called lines, a signaling device for each link circuit controlled by a 60 called line to give certain indications, automatic means for causing the signaling device to give a different indication upon the expiration of a predetermined time after the response of the called line, and operator-controlled means for maintaining the status of the automatic means at any time prior to the expiration of the predetermined time.

4. In a telephone exchange system, a plurality of lines having substations thereon 75 and terminating at a central office, a plurality of link circuits thereat for interconnecting the lines of calling and called stations, a supervisory relay for each link circuit jointly controlled by the operator and a 80 called station, a signaling device controlled thereby for producing a signal upon the restoration of the receiver at the called station, timing mechanism controlled by the supervisory relay, said mechanism starting 85 to operate upon the response of the called station, means controlled by the timing mechanism to cause a different signal to be produced by the signaling device after such mechanism has operated for a predetermined 90 period of time, operator-controlled means for restoring the timing mechanism to normal at any time prior to the expiration of the predetermined period, and additional operator-controlled means for maintaining 95 the status of the timing mechanism at any time prior to the expiration of the predetermined period.

5. In a telephone exchange system, a plurality of lines terminating at a central office, a plurality of link circuits thereat for interconnecting the lines, a timing means for association therewith and adapted for continuous operation for a predetermined period, means controlled jointly by the operator and the subscriber on a connected line for starting the timing means, operator controlled means for holding the timing means at any time prior to the expiration of such period, and means automatically operative upon the completion of the operation of the timing means to restore said timing means to its normal condition.

In witness whereof, I hereunto subscribe my name this 26th day of September, A. D. 115 1918.

CHARLES W. KECKLER.
